Primary Examiner — Holly E Thurman(74) *Attorney, Agent, or Firm* — Bruce S. Shapiro(57) **CLAIM**

The ornamental design for a drill holster, as shown and described.

DESCRIPTION

FIG. 1 is a front perspective view of our new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines shown in the drawings illustrate portions of the drill holster that form no part of the claimed design.
